US00D461604S

(12) **United States Design Patent** (10) Patent No.: **US D461,604 S**
Martin et al. (45) Date of Patent: **** Aug. 13, 2002**

(54) **HOUSING FOR A BLOWER/VACUUM**

(75) Inventors: **David J. Martin**, Eden Prairie; **Steven J. Svoboda**, Bloomington; **Chadwick A. Shaffer**, Oakdale, all of MN (US)

(73) Assignee: **The Toro Company**, Bloomington, MN (US)

(**) Term: **14 Years**

(21) Appl. No.: **29/136,944**

(22) Filed: **Feb. 9, 2001**

(51) LOC (7) Cl. **15-05**

(52) U.S. Cl. **D32/15**

(58) Field of Search **D32/1, 15, 16, D32/17, 25; 15/328, 329, 330, 344, 345, 404, 405, 414, 339, 415.1, 413, 326; 417/236, 423.1, 423.3, 363**

(57) **CLAIM**

The ornamental design for a housing for a blower/vacuum, as shown.

DESCRIPTION

FIG. 1 is a left front perspective view of a housing for a blower/vacuum according to one embodiment of the present invention;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof; and,

FIG. 7 is a bottom plan view thereof.
